COMBINED DISPLAY AND STORAGE SHELTER FOR TIRES OR THE LIKE

Harvey J. Smith, Greensboro, N.C., assignor to Modern
Metal Products Company, Greensboro, N.C., a corpo-
ration of North Carolina

Filed Mar. 10, 1961, Ser. No. 64,211

Term of patent 14 years

(Cl. D13—1)

FIG. 1

FIG. 2

FIG. 3

FIG. 4

FIGURE 1 is a front perspective view of a combined display and storage shelter for tires or the like embodying my new design shown in open position;

FIGURE 2 is a somewhat enlarged perspective view of the article in closed position;

FIGURE 3 is an enlarged rear perspective view thereof; and,

FIGURE 4 is a side elevational view thereof.

I claim:

The ornamental design for a combined display and storage shelter for tires or the like, as shown.
